CLAIM

The ornamental design for a wine bucket, as shown and described.

DESCRIPTION

FIG. 1 is a front elevational view of a wine bucket showing my new design;

FIG. 2 is a rear elevational view;

FIG. 3 is a left side elevational view;

FIG. 4 is a right side elevational view;

FIG. 5 is a top plan view;

FIG. 6 is a bottom plan view; and,

FIG. 7 is a perspective view of the wine bucket having wine bottles stored therein.

The broken lines showing the wine bottles in FIG. 7 are included for the purpose of illustrating the use of this wine bucket only and form no part of the claimed design.
